(57) **CLAIM**

The ornamental design for a sonic toothbrush, as shown and described.

DESCRIPTION

FIG. 1 is a front perspective view of a sonic toothbrush, in accordance with my new design.

FIG. 2 is a front elevation view of the sonic toothbrush shown in FIG. 1.

FIG. 3 is a side elevation view, taken from the left side of FIG. 2, of the sonic toothbrush shown in FIG. 1.

FIG. 4 is a rear elevation view of the sonic toothbrush shown in FIG. 1.

FIG. 5 is a side elevation view, taken from the right side of FIG. 2, of the sonic toothbrush shown in FIG. 1.

FIG. 6 is top plan view of the sonic toothbrush shown in FIG. 1; and,

FIG. 7 is a bottom plan view of the sonic toothbrush shown in FIG. 1.

The broken lines illustrate portions of the sonic toothbrush that form no part of the claimed design.
